UNITED STATES PATENT OFFICE

JEAN GUSTAVE BASSIÈRE, OF PARIS, FRANCE

TUBULAR ELECTRIC RESISTANCE

Application filed May 16, 1928, Serial No. 278,118, and in France June 4, 1927.

The present invention relates to a tubular electric resistance through which a fluid can be circulated.

When an electric current is supplied to 5 said tubular resistance, a part of the heat produced in said resistance is drawn off by the fluid circulating through the tube.

With this arrangement, the whole of the 10 circulating fluid is utilized to absorb the heat of the resistance element, so that the exchange of heat between the resistance and the circulating fluid will be quite considerable, and will take place in particularly favourable conditions.

15 This exchange of heat may be utilized either for cooling the resistance, or for heating the circulating fluid, or for both purposes simultaneously.

Tubular electric resistances are known in 20 which a metallic band of suitable cross-section is formed into a helix with overlapping edges so as to constitute a continuous tubular element. Between the adjacent edges of the successive coils of said helix is inserted a strip 25 of insulating material which serves both for making the tube fluid-tight and for electrically insulating the individual helix coils from one another.

The object of the invention is to provide 30 means whereby a sufficient lengthwise elasticity is given to said tubular resistance in order that said tube may be adapted to follow the expansions and contractions due to the great variations in the temperature, and 35 without subjecting the insulating joint to exaggerated stresses prejudicial to its good state.

In the appended drawing, which is given 40 solely by way of example:

Fig. 1 is a sectional view of the metallic band used for the construction of the tubular resistance element according to the invention.

Fig. 2 is a view of a tubular resistance element according to the invention, the lower 45 half of said view being a lengthwise section, the upper half being an external view.

The cross section of the band, as shown in Fig. 1, comprises the edge parts 1 and 2 and 50 the central part 3. In order to constitute the

tubular electric resistance, the metallic band is formed into a cylindrical, prismatic or polygonal helix, so that the edge part 1 of the metallic band in one individual helix coil will cover the edge part 2 of the metallic 55 band of the adjacent helix coil (Fig. 2).

Between the overlapping edges 1 and 2 of two successive helix coils is inserted an insulating strip 4, which is wide enough to extend somewhat beyond the free edges of 60 the parts 1 and 2 at the interior and at the exterior of said tube, and it will thus insulate the adjacent coils in such manner that the current passing laterally from one turn to another will be negligible. The insulating 65 band assumes the form shown at 4, Fig. 2.

The resistance tube thus obtained may readily transmit its heat to the circulating fluid. Since the insulating band serves only to provide electrical insulation for the small 70 difference of potential between two adjacent coils, its thickness is but small; a good thermic contact is thus afforded between the edges 1 and 2 of the adjacent coils. Moreover, the surface of the metallic band in direct 75 contact with the circulating fluid is a considerable fraction of its total internal surface. These conditions will all contribute to assure a very active exchange of heat between the said tube and the circulating fluid. 80

Due to the curved form of the connection, which is given by way of example, the joint will have a great mechanical strength. The middle part 3 of the said band in its bent form will be sufficient to give the tube a good lengthwise elasticity in order that the stresses caused by expansion and contraction due to temperature changes, to vibrations or to flexions, will not expose the joint to excessive efforts which would offer prejudice 90 to its preservation.

The metal of the said metallic band employed for the manufacture of the resistance tube may be selected as desired, and this will depend upon each particular application.

95 In a same manner the material forming the band 4 may differ according to the applications of the said resistance tubes; it need not have a very high insulation, since the tension between the coils is but small. It may be 100

also fireproof, and may consist of asbestos or mica if the tubular resistance is employed at high temperatures. It may consist of organic material, such as paper, when operating at low temperatures.

Having now described my invention, what I claim as new and desire to secure by Letters Patent is:

1. A tubular electric resistance comprising a band of electrically conducting material provided between its edges with a yielding longitudinal central portion adapted to expand and to contract transversely, said band being formed into an helix with the edges overlapping on either side of said yielding portion so as to constitute a tubular element having a lengthwise elasticity, and a strip of electrically insulating material inserted between the adjacent edges of said band and independent of said yielding portion, whereby the insulating joint formed by said strip remains unaltered during the expansions and contractions of said yielding portion.
2. A tubular electric resistance comprising a band of electrically conducting material provided between its edges with a longitudinal central corrugation adapted to expand and to contract transversely, said band being formed into an helix with the edges overlapping on either side of said corrugation so as to constitute a tubular element having a lengthwise elasticity, and a strip of electrically insulating material inserted between the adjacent edges of said band and independent of said corrugation, whereby the insulating joint formed by said strip remains unaltered during the expansions and contractions of said corrugation.

In testimony where I have signed my name to this specification.

JEAN GUSTAVE BASSIÈRE.
